UNITED STATES PATENT OFFICE.

JOHN H. BOWERS, OF MOUND CITY, MISSOURI.

DOUGH-KNEADER.

SPECIFICATION forming part of Letters Patent No. 400,187, dated March 26, 1889.

Application filed August 16, 1888. Serial No. 282,845. (No model.)

To all whom it may concern:

Be it known that I, JOHN H. BOWERS, a citizen of the United States of America, residing at Mound City, in the county of Holt and 5 State of Missouri, have invented certain new and useful Improvements in Dough-Kneaders; and I do hereby declare the following to be a full, clear, and exact description of the invention, such as will enable others skilled 10 in the art to which it appertains to make and use the same, reference being had to the accompanying drawings, and to letters or figures of reference marked thereon, which form a part of this specification.

15 My invention relates to certain new and useful improvements in dough-kneaders, the object being to provide a device whereby the dough may be rolled, worked, or kneaded, said device consisting, essentially, of a longitudinally-moving board having rack-bars secured thereto, a vertically-adjustable roller located above said board and provided with gear-wheels connected by intermediate pinions to the rack-bars, the aforesaid roller having a 20 shaft and operating crank-handle, which shaft is supported in vertically-adjustable bearings, as will be hereinafter fully set forth, and specifically pointed out in the claims.

25 In the accompanying drawings, Figure 1 is 30 a perspective view of a dough-kneader constructed in accordance with my improvement. Fig. 2 is a longitudinal section.

A refers to the side pieces, which constitute the frame of the apparatus, they being rigidly 35 bolted or otherwise secured to the top of a flour-chest or table. The lower portions at the corners of these side pieces have formed thereon blocks or bearings *a a*, with perforations for the reception of gudgeons, which 40 support the rollers B B, said rollers having central circumferential recesses, *b*.

On the inner edges of the side frames, A, between the blocks *a a*, are formed webs *c*, through which the connecting bolts or screws 45 pass for securing said side pieces rigidly to a suitable support. The side pieces, A, extend upwardly and are shaped substantially as shown, they being provided with extended or projecting portions *d d*, to which are secured 50 stub-shafts, which carry pinions *e e*. These

frames are also provided with segmental slots D D, and the outer edges of the frames adjacent to these slots have teeth *f* formed therein.

Between the slots D D and the shafts of the pinions *e* are pinions through which pass stub-shafts *e'*, which hold in place pinions *g* and the ends of the bifurcated levers G.

Over the rollers B B and supported thereon is a dough-board, F, to the under side of which is secured a guide-strip, *f'*, which lies in a central recess formed in said rollers. The edges of this dough-board F have secured thereto rack-bars *h h*, which engage with the pinions *e*, these pinions meshing with the pinions *g*, which rotate freely on the stub-shafts *e'*. 65

The roller H is rigidly mounted on a shaft, H', and to said roller upon the shaft, so as to move therewith, are secured cog-wheels I, which engage with the pinions *g*. The shaft H' passes through the side pieces of the bifurcated levers G G, and also through the segmental slots D, and these levers G carry spring-pawls which engage with the teeth *f*, so as to hold the roller H in position, and by adjusting these levers the distance of the 70 roller from the board F may be varied.

The operation of my invention is as follows: The dough to be kneaded is placed upon the board F, and as the crank-handle is turned said board carrying the dough is passed under the roller, the direction of the rotary movement of the crank-handle being changed as the end of the board is reached, thus causing the board to reciprocate as the dough is worked. The roller H can be depressed by 80 releasing the spring-pawls and depressing the levers, so as to further compress and work the dough upon the kneading-board.

I claim—

1. The combination, in a dough-kneader, of 90 the side frames carrying pinions *g* and *e*, and having rack-teeth in one part of the edge thereof, bifurcated levers G G, pivoted to said frame, said levers forming bearings for a crank-shaft carrying a geared roller, and 95 spring-actuated pawls adapted to engage the rack-teeth on the side frames for adjusting the bifurcated levers and roller, the said frames having slots through which the roller-shaft passes, and a kneading-board having 100

rack-teeth, the parts being organized substantially as shown, and for the purpose set forth.

2. In a dough-kneader, the combination of a frame, a reciprocating kneading-bed mounted therein having an integral guide-spline at the center of the bottom thereof, grooved rollers journaled in said frame, with the grooves of which the guide-spline of the kneading-bed is in engagement, adjusting-levers pivoted to upper extensions of the frame on each side thereof, a crank-shaft having bearings in said levers, and a revoluble kneading-roll attached to said crank-shaft operating to reciprocate the kneading-bed and adapted to have a temporary stationary adjustment toward or away from said bed by means of the levers, substantially as described.

3. In a dough-kneader, the combination, with a frame having a reciprocating kneading-bed therein, adjusting-levers pivoted to the upper part of said frame on each side thereof, a crank-shaft having bearing in said levers, and a revoluble kneading-roll attached to said crank-shaft, and adapted to reciprocate said kneading-bed, substantially as described. 20 25

In testimony whereof I affix my signature in presence of two witnesses.

JOHN H. BOWERS.

Witnesses:

JOHN KENNISH,
LANES BLAIR.
